UNITED STATES PATENT OFFICE.

SAMUEL T. WELLMAN AND CHARLES H. WELLMAN, OF CLEVELAND, OHIO,
ASSIGNORS TO THE WELLMAN-SEAVIER ENGINEERING COMPANY, OF
SAME PLACE.

APPARATUS FOR CASTING AND HEATING INGOTS.

SPECIFICATION forming part of Letters Patent No. 627,835, dated June 27, 1899.

Application filed February 23, 1897. Serial No. 624,561. (No model.)

To all whom it may concern:

Be it known that we, SAMUEL T. WELLMAN and CHARLES H. WELLMAN, citizens of the United States, and residents of Cleveland, 5 county of Cuyahoga, and State of Ohio, have invented certain new and useful Improvements in Apparatus for Casting and Heating Ingots, of which the following is a specification, the principle of the invention being 10 herein explained and the best mode in which we have contemplated applying that principle so as to distinguish it from other inventions.

The annexed drawings and the following 15 description set forth in detail certain mechanism embodying the invention, such disclosed means constituting but one of various mechanical forms in which the principle of the invention may be used.

20 In said annexed drawings, Figure I represents a plan of our improved steel plant. Fig. II represents a side elevation of the heating-furnace of said plant. Fig. III represents a longitudinal vertical cross-sectional view of 25 one end of said furnace, showing the combustion-chamber. Fig. IV represents a transverse cross-sectional view of the same. Fig. V represents a detail view of a portion of two 30 of the flanged plates of the furnace-wall suitably secured together. Fig. VI represents a view in detail of the entire mold.

The furnaces or converters A are suitably arranged adjacent to a track B, a portion of 35 which is embraced and included within a heating-furnace C. The track before entering the said furnace drops on an incline for a short distance, and upon emerging therefrom it rises to its original level. This depressed portion is kept filled with water by 40 suitable water connections.

A traverser D, carrying a tilting or other suitable ladle d, which may be filled from the furnaces A, runs over the said track B.

Mold-buggies E run upon the track B and 45 carry the ingot-molds e, which are filled from the ladle d.

A mold-stripper F is suitably located over track B and is adapted to strip the molds from the ingots, leaving them bare upon the buggies before entering the heating-furnace.

The buggies E are provided with a fire-brick stool f, of somewhat larger surface dimensions than the base of the ingots. The molds are so placed that the stool f receives all of the hot-metal contact from the ingot and is soon 55 heated to a high degree. The ingots are therefore not chilled upon being cast thereon and are thus much more evenly heated in the furnace than would be the case if the ingot were cast upon a substance having a lower 60 degree of temperature. The fire-brick, being of low conductivity and having a high degree of specific heat, retains its temperature, and once having been heated it is always ready 65 and hot for the next casting. The fire-brick 70 is easily removable and can on burning out be easily replaced or repaired. The buggies are further formed with flanges f', adapted to center the mold and thus secure the proper relative position of the ingot and the stool f. 75 Overlapping sides f² extend over the wheels of the buggy-truck and are cut off squarely at the front and rear, extending downwardly to within a short distance of the road-bed. The ends of the sides are adapted to close 80 upon and fit against the adjacent end of the next buggy, as is shown in Fig. III. These sides extend into the water, filling the depression, and thus protect the trucks of the buggies from destruction by the heat of the furnace. 85 Those represented in the drawings carry two. Those represented in the drawings carry two.

The furnace C is constructed in the form of an elongated chamber lined with a fire-brick 85 lining c' built upon the wall in the usual manner, the said walls being constructed in sections of iron or steel plates provided at their edges with suitable angles whereby the said sections may be bolted up in the field. 90 The lining, however, does not extend to the bottom of the furnace, but only to within a short distance of the top of the buggy, which it overlaps to a distance such that just sufficient space is left between the two brick walls 95 to permit of the safe passage of the ingot and buggy therebetween. A very small portion of the top of the buggy is thus exposed. An air-passage c² is provided between the arch of the flue or chamber and the covering c³, 100

through which air admitted into the forward end passes over the heated arch, becomes heated and enters the combustion-chamber c^4 , where it mingles with gas from the gas-flue c^5 , leading from a suitable producer. The hearth of the combustion-chamber is raised above the bottom or rail-bed of the furnace, and the track passes out of the chamber beneath the said hearth. The height from the top of the rails—that is, from the base of the transporting-cars to the lower surface of the hearth above the cars when passing beneath the hearth—is less than the height from said base to the top or highest point of the ingot while being transported upon said cars. The cars when unloaded may hence pass out beneath the combustion-chamber. A door c^6 is provided in the top of the furnace just beyond the end of the bottom of the combustion-chamber, through which the ingots may be lifted from the buggies. Suitable doors c^7 are also provided for the admission and exit of the buggies.

A suitable mechanism is provided at the entrance of the furnace for properly moving the cars through the furnace.

The operation of the plant is as follows: The molten metal is run into the ladle d , suspended over the track B, from which it is poured into the molds e , standing on the buggies E , or is poured directly into molds. After the metal is sufficiently set the buggies are run under the stripper F , where the molds are stripped, leaving the ingots bare. They are thereupon run into the furnace, through which they travel slowly and become gradually heated until they reach the end of the furnace beneath the unloading-door c^6 , whence they are removed and are ready for the rolls.

The furnace may also be used for reheating cold ingots.

The action of the furnace in the case of the introduction of cold ingots for reheating is somewhat different from the action in the case of the hot ingots right from the molds, the action in each case being salutary.

In the case of cold ingots the heat is brought up gradually by means of the progression of the ingot from the coolest end of the furnace to the hottest, thereby avoiding the contingency of melting off the outside while the inside is cold, which occurs in the usual method of placing the cold ingot directly into the heating-furnace and subjecting it immediately to the extreme temperature, so that by my improved means the ingot is heated up evenly and to nearly the required heat before being subjected to the final temperature.

In the case of hot ingots the molds are stripped off as soon as the outer metal is sufficiently set, which leaves the inside of the ingot in a liquid state. By introducing the ingot in this manner into the coolest end of our furnace the molten metal is given a chance to set, and the outside and inside gradually reach the same temperature from different directions. Meanwhile, however, the ingot

has been progressing into the furnace, so that when it reaches the end of its travel it also is in a homogeneous evenly-heated condition, a condition, as is well known, appreciated by the steel-worker. Each buggy then constitutes one of a continuous train, which gradually on removal of one of the buggies at the exit progresses, the empty buggies being returned for repeated use on the track B', connected by a suitable switch b with track B. The entire operation of casting and reheating is thus accomplished without the necessity of removing the ingot from the buggy, and the heat of combustion and of products of combustion is utilized to heat the air requisite for combustion, and also in preheating the ingots before being given their final heat.

Other modes of applying the principle of our invention may be employed instead of the one explained, change being made as regards the mechanism herein disclosed, provided the means covered by any one of the following claims be employed.

We therefore particularly point out and distinctly claim as our invention—

1. The combination of apparatus for producing molten metal, a car-track adjacent to said apparatus, a car adapted to run upon said track, means for casting ingots upon said car, a heating-furnace embracing a portion of said track, said portion being depressed below the level of the track located without said furnace, water covering said depressed portion, said car adapted to travel through said heating-furnace, substantially as set forth.

2. The combination of apparatus for producing molten metal, a car-track adjacent to said apparatus, a second track adjacent to said first track and suitably connected therewith, a car adapted to travel upon said tracks, means for casting ingots upon said car, a heating-furnace embracing a portion of said first track, said portion being depressed below the level of the track without said furnace, water covering said depressed portion, said car adapted to travel through said heating-furnace, substantially as set forth.

3. The combination of apparatus for producing molten metal, a car-track adjacent to said apparatus, a car adapted to travel upon said track, a heating-furnace embracing a portion of said track, said embraced portion being depressed below the level of the track without said furnace, water in said depressed portion, and means adapted to gradually move said car through said furnace, substantially as set forth.

4. The combination of apparatus for producing molten metal, a car-track adjacent to said apparatus, a car adapted to travel upon said track, an elongated heating-furnace embracing a portion of said track, said embraced portion being depressed below the level of the track located without said furnace, water in said depressed portion, said heating-furnace provided with a hot and a cool end, and means adapted to advance said car gradually from

said cool to said hot end, substantially as set forth.

5. The combination of apparatus for producing molten metal, a car-track adjacent to said apparatus, a car adapted to travel upon said track and adapted to carry an ingot-mold, means for casting metal into said mold, a heating-furnace for receiving said car and ingot upon the latter, said furnace embracing a portion of said track, said portion depressed below the level of the track located without the furnace, water in said depression, and means for stripping the molds from the ingot and car before the latter enters the furnace, substantially as set forth.

6. The combination of apparatus for producing molten metal, a car-track adjacent to said apparatus, a car adapted to run upon said track, means for casting ingots upon said car, a heating-furnace embracing a portion of said track, said portion being depressed below the level of the track located without said furnace, water covering said depressed portion, said car adapted to travel through said furnace, and means for unloading said cars before their exit from the said furnace, substantially as set forth.

7. The combination of a heating-furnace

having a combustion-chamber at one end, means for transporting ingots from the other end through the furnace, said means passing out beneath said combustion-chamber, and means for unloading said transporting means before leaving the furnace, substantially as set forth.

30

8. The combination of a car-track, a heating-furnace embracing said track and consisting of a heating-chamber provided with a combustion-chamber at one end, said track passing out of the furnace beneath said combustion-chamber, a car adapted to run through said chamber upon said track, means for moving said car from the opposite end of the chamber toward the combustion-chamber, and means for unloading said car intermediately of said opposite end and of the said combustion-chamber, substantially as set forth.
